UNITED STATES PATENT OFFICE.

HENRY A. WISE WOOD, OF NEW YORK, N. Y., ASSIGNOR TO WOOD & NATHAN COMPANY, OF NEW YORK, N. Y., A CORPORATION OF NEW YORK.

PRINTED AND SLIP SHEET SEPARATING APPARATUS.

1,162,895.

Specification of Letters Patent.

Patented Dec. 7, 1915.

Application filed March 18, 1914. Serial No. 825,594.

To all whom it may concern:

Be it known that I, HENRY A. WISE WOOD, a citizen of the United States, residing at New York, in the county of New York and State of New York, have invented a new and useful Printed and Slip Sheet Separating Apparatus, of which the following is a specification.

The object of this invention is to provide an apparatus by which a pile of sheets consisting of printed sheets and slip-sheets can be separated, the printed sheets put in a flat pile or passed to a folder or other sheet manipulating apparatus either side up, and the slip sheets deposited in a pile by themselves ready for use again.

Referring to the drawings and in detail, Figure 1 is a side elevation of one form of my apparatus. Fig. 2 is a side elevation on an enlarged scale of part of the apparatus shown in Fig. 1. Fig. 3 is a cross-sectional view taken on the line 3—3 of Fig. 2. Fig. 4 is a side elevation taken on the side opposite to the view shown in Fig. 2, and Fig. 5 is a diagrammatic view illustrating a modification which may be made in the general arrangement of the apparatus.

Referring to the drawings, an apparatus is shown wherein the printed sheets can be delivered flat with either the last printed side up or down as desired.

In said drawings A designates a pile of interposed printed and slip-sheets. This pile is laid upon a suitable table 20 and the sheets are fed one at a time from said pile either by any of the usual automatic feeders or by hand. The apparatus for manipulating the sheets thus fed is arranged between two side frames 21—21. The sheets as they are fed first pass in between two sets of tapes, an upper set 22 and a lower set 23. The upper set of tapes is trained around tape pulleys 96 and 97 continuously driven by any suitable means, not necessary to show, so that the said tapes 22 will run continuously in the direction indicated by the arrows. The lower set of tapes 23 is trained around tape pulleys 28. Then the tapes pass around a roller 32 journaled in carriers c—c, and then around pulleys 33—34 and 36 back to the pulleys 28. The pulleys 33 and 28 are arranged on shafts which are journaled in the side frames 21—21. The pulleys 34 and 36 are mounted on shafts 340 and 360 re-

spectively, which are journaled in frames or weights 37 which are fitted to slide on ways 38 formed or secured to the side frames 21—21. By this arrangement, as the tape roller 32 is reciprocated by the means hereinafter described, a constant tension will be kept on the tapes 23.

The carriers c—c for the roller 32 are arranged so as to be capable of a reciprocating motion on ways 51—51 formed or secured to the side frames 21—21. These carriers c—c are provided with rollers 52 to run on said ways. The carriers are reciprocated by means of a crank-pin 53 mounted on a disk 54 which crank-pin connects by link 55 to a lever 56 mounted on a shaft 57 journaled in the side frames 21—21. Arms 58—58 are secured to said shaft 57, and each carrier c is connected by a link 59 to one of said arms 58. The disk 54 is geared as hereinafter described to turn once for each sheet and slip-sheet manipulated in the machine, and by this arrangement, the carriers c—c will be reciprocated once for each sheet and slip-sheet.

The shaft of the roller 32 is loosely journaled in the carriers c—c, and loosely arranged on the shaft is a gear 60 which meshes with a rack 61 cut or formed on the underside of one of the ways. A ratchet-wheel 62 is secured on the end of the shaft 60 of the roller 32, and engaging the ratchet-wheel is a pawl 63 pivoted on the gear 60, which pawl is held in engagement with the ratchet-wheel by a spring 64. By this arrangement, as the roller 32 moves forward or to the right, the roller 32 will not be turned as the pawl will run idly around the ratchet-wheel, but when the roller 32 is moved in the opposite direction, the same will be rotated by the mechanism described to peel the tapes 23 from under the slip-sheet to allow a delivery of the same.

The roller 32 will deliver the slip-sheets upon a delivery table B. This delivery table is provided with wheels 65 which run on tracks 66 extending laterally of the mechanism. By this arrangement, the delivery table can be slid in or withdrawn laterally of the machine. The delivery table is provided with bars 67 which project from each corner. These bars are engaged by loops formed in the end of cables 68, there being two cables on each side of the machine. The

longest cable at each side of the machine extends over a pulley 69, and the two cables at each side of the machine are trained over concentric pulleys 70—70, and are secured at their ends to a drum 71 arranged on the end of a shaft 72, there thus being two drums, one at each side of the machine. These drums are operated to lower the delivery table B as the pile of slip-sheets accumulates thereon by the following mechanism: A worm-wheel 73 is secured on the shaft 72 and meshing with the same is a worm 74 secured on a shaft 75 journaled in brackets just inside the framing. The shaft 75 is driven by a worm-wheel 76 which is driven by a worm 77 arranged on a vertical shaft 78 which carries a worm-wheel 79, engaging which is a worm 80 secured on the end of a shaft 81. Adjustably secured on the shaft 81 is a friction disk 82 which bears on the side of a large gear 83 mounted on a shaft 84. By adjusting the friction disk on the shaft 81 the rate of descent of the table B can be adjusted. The worm wheel 76 is loosely arranged on this shaft, and the same has suitable projections 85. A handle is keyed on the end of the shaft 75, and is held normally in engagement with the projections 85 by a spring, not shown, whereby the worm 76 will normally drive the shaft 75.

Power may be applied to the apparatus described by means of a driving belt passing around a driving pulley 91 arranged on a shaft 92 and carrying a pinion 93 meshing with the gear 83 previously referred to.

Intermingled with the lower set of tapes 23 is a set of fly-fingers 98 which are secured on a shaft 99 journaled in the framing. These fly-fingers are operated to take the sheet passing out on the tapes 23 and turn the same over and deliver the same on the delivery table C arranged substantially in the same manner as the delivery table B. The delivery table B is slid forward or toward the front from the position shown in Fig. 1 for delivery, and the table C is pushed in the opposite direction. The table C is lowered by supplemental cables 100 from the drums 71—71 in the same manner as the table B.

A pinion 101 is arranged on the rear end of the shaft 84, and the same meshes with and engages a gear 102 turning loosely on a stud shaft 103 and carrying a cam 104. Engaging the groove of this cam is a roller mounted on a pivoted lever 105 secured on the end of a short shaft 106 journaled in a bracket projecting from the framing. On the other end of the shaft 106 is arranged a lever 107 pivoted to the end of which is a rack 108 which engages a gear 109 secured on the end of the fly-finger shaft 99. The rack 108 is kept in engagement with the gear 109 by a roller 110. The reduction between the pinions 101 and 102 is two to one.

It will be noted that the cam 104 is made concentric for about one-half of its periphery, and only has operative sections for the other half of its periphery.

In operation, the delivery table is run on its rails in position in the machine, and the cables 68 are engaged therewith. The handle 86 is then pulled out so as to clear the projections 85, and the shaft 75 is turned to its highest position. Then the handle 86 is released so that the worm-wheel 76 will be locked to the shaft 75 and then as the machine operates, the delivery table B will be lowered as the pile of slip-sheets accumulates thereon, until it comes down to its rails, when it is slid laterally out of the machine to remove the slip-sheets. By this mechanism a large pile of slip-sheets can be delivered without stopping the machine, and the delivery of each sheet takes place accurately in the same position, owing to the automatic lowering of the delivery table. The adjustable friction disk provides for an adjustment so that this lowering of the delivery table can be timed accurately to the delivery of the slip-sheets. The first sheet passing between the tapes 22 and 23 is carried out over the delivery table B. Suppose the fly-fingers 98 are under the set of lower tapes 23 as this action takes place. Just as the pulley 32 reaches the end of its forward movement, and as this sheet reaches the end of its forward movement on said tapes 23, the fly-fingers will come into operation, and the sheet will be lifted by said fly-fingers, turned over, and delivered on the delivery table C. The fly-fingers, by reason of the construction of the cam described, will remain in delivery position as the next sheet passes into the apparatus between the tapes 22 and 23, and as the same is advanced over the delivery table B, the fly-fingers will not be under the same. Therefore, during the backward or left-hand movement of the pulleys 32 this second sheet will be delivered on the table B. Thus the first sheet will be turned over and delivered on the table C, while the second sheet will be delivered on the table B without being turned over. Thus if it is desired to turn over and deliver the printed sheets, the feed is timed so that the printed sheets will be deposited upon the table C, and the slip-sheets on the table B; while on the other hand, if it is desired to deliver the printed sheets without turning the same over, the feed is timed so that the printed sheets will be delivered on the delivery table B and the slip-sheets on the table C.

This apparatus can be employed to great advantage when the sheets are printed upon one side at a time. In the first operation of separation from the slip-sheets, the printed sheets can be turned over so that they are ready to go back to the printing press again

with their unprinted sides up. After the sheets have been perfected they may be separated from the slip-sheets with either side up as desired for the further manipulation of the sheets. This operation can well be carried out as it is practically immaterial which side up the slip-sheets are used, but if the above operation is carried out in connection with perfecting sheets, it will be noticed that the slip-sheets will be turned over once for every two separations from the printed sheets, which makes an advantageous way of using a pile of slip-sheets.

The modification shown in Fig. 5 is substantially the same except that a pair of folding rollers 115 and 116 are arranged beyond the delivery table C, and a tucker blade 117 is arranged to coöperate therewith. A swinging or folding apron 118 is arranged in connection with one of the folding rollers. By this arrangement, by swinging the folding apron down in position so that the fly will deliver the sheets thereon, the printed sheets may be passed to the folder, or by turning the folding apron up as shown in dotted lines, the printed or slip-sheets may be delivered on the table C. This is an advantageous arrangement when it is desired to finally fold the printed sheets after they have been perfected.

Many other modifications may be worked out without departing from the scope of my invention as expressed in the claims.

Although I have illustrated and described only a single form of the invention I am aware of the fact that modifications can be made therein by any person skilled in the art without departing from the scope of the invention as expressed in the claims. Therefore, I do not wish to be limited in these respects, but

What I do claim is:—

1. An apparatus for separating intermingled printed and slip-sheets, comprising means for advancing sheets, a sheet delivery mechanism, means whereby the same will act to deliver every alternate sheet, and a second delivery mechanism arranged to deliver the other sheets the opposite side up as compared with the first delivery mechanism. 45

2. An apparatus for separating intermingled printed and slip-sheets, comprising means for advancing sheets, a sheet delivery mechanism, means whereby the same will act to deliver certain sheets in regular order, and a delivery mechanism arranged to turn over and deliver the other sheets. 55

3. An apparatus for separating intermingled printed and slip-sheets, comprising means for advancing sheets, a reciprocating sheet delivery mechanism, means whereby the same will act to deliver every alternate sheet, a fly delivery mechanism arranged to act on the other sheets, and a folding mechanism. 60 65

4. In an apparatus for separating intermingled printed and slip sheets, the combination of means for moving the sheets one at a time along a path, means for delivering certain of said sheets, and means for automatically intercepting a sheet at regular intervals, preventing it from passing to said delivering means, and delivering it the other side up. 70 75

In testimony whereof I have hereunto set my hand, in the presence of two subscribing witnesses.
